Primary Examiner — Sandra L Morris(74) *Attorney, Agent, or Firm* — Michael Best and Friedrich LLP(57) **CLAIM**

The ornamental design for a disc player, as shown and described.

DESCRIPTION

FIG. 1 is a perspective view of a disc player showing my new design;

FIG. 2 is a front elevational view thereof;

FIG. 3 is a rear elevational view thereof;

FIG. 4 is a left side elevational view thereof;

FIG. 5 is a right side elevational view thereof; and

FIG. 6 is a top plan view thereof; and,

FIG. 7 is a partially enlarged perspective view thereof at the location surrounded by the dot-dash broken lines 7 of FIG. 1.

The broken lines illustrating unclaimed portions of the disc player form no part of the claimed design.

1 Claim, 7 Drawing Sheets(56)
